UNITED STATES PATENT OFFICE.

ALBERT J. DRONSFIELD, OF PROVIDENCE, RHODE ISLAND.

HUMIDIFYING APPARATUS.

1,002,905.

Specification of Letters Patent. Patented Sept. 12, 1911.

Application filed December 27, 1910. Serial No. 599,465.

To all whom it may concern:

Be it known that I, ALBERT J. DRONSFIELD, a citizen of the United States, residing at Providence, in the county of Providence and State of Rhode Island, have invented certain new and useful Improvements in Humidifying Apparatus, of which the following is a specification.

My invention relates to that class of humidifying apparatus wherein a jet of air under pressure, steam, or other fluid, creates a vacuum to raise the water, and also pulverizes the particles of the latter as they are discharged from the nozzle. Such an apparatus is that shown in U. S. Letters Patent No. 869,945 dated November 5th, 1907. In this type of apparatus during the raising and lowering of the fluid pressure due to starting or stopping of the flow of the fluid there is a period of time during which the pressure is gradually raised or lowered at the nozzle, and at such times the fluid pressure is insufficient to atomize or pulverize the liquid which exudes from the nozzle in drops until a certain pressure of the fluid has been reached sufficient to properly atomize the liquid. The resultant dripping of the liquid from the nozzle upon the floor, machinery, or other objects below the system is highly objectionable and injurious.

The essential objects of my invention are to prevent the dripping; and to attain this end automatically, certainly and in a simple and inexpensive manner, and by means adapted to use in existing systems without reorganization of the latter.

Other objects will be hereinafter set forth.

To the ends above set forth and referred to essentially my invention consists in such novel parts and combinations and arrangements of parts as fall within the scope of the appended claims.

In the accompanying drawings which form a part of this specification, and wherein like reference characters indicate like parts throughout the views, Figures 1 and 2 are side and front elevations respectively of the vaporizing portion of a humidifying apparatus embodying my invention, and in the present instance comprising certain of the parts disclosed in the Letters Patent above referred to. Fig. 3 is a section taken on line α α of Fig. 2. Fig. 4, a section on line y y of Fig. 1, and Fig. 5, is a detail side elevation of the valve cap.

The structure herein shown comprises a liquid conduit 1 provided with a coupling 2 carrying an upright nipple 3 supporting a hollow cap 4 from which extends a liquid supply pipe 5 which is secured by a coupling 6 to a liquid plug 7 which is threaded as at 8 in a transverse cylindrical opening 10 in the head 11. Seated in the end of the plug 7 concentric therewith and extending into the cylindrical opening or chamber 10 is a nozzle 14. The fluid conduit 18 has a coupling 19 supporting a vertical pipe 20 provided with threads 21 engaging internal threads 22 of a valve case 23 comprising in detail an opening 24 leading to a central chamber 25 communicating through an opening 26 at right angles to the opening 24 with a passage 27 leading to a chamber 28 in the upper extension 29 of the case 23. The case 23 is provided with a horizontal extension or cylinder 32 provided with a central piston chamber constituting a part of chamber 25. The outer end of the cylinder is provided with internal threads 33 engaging external threads 34 upon the reduced forward portion 35 of a plug or cap 36 provided with an opening 37 in which is seated this outer end of a helical spring 39. A central hole 40 in the end of the plug 36 opens into the chamber or opening 37 to form a free vent for the piston chamber. The exterior of the plug 36 is hexagonal as at 41 to facilitate the use of a wrench. The forward end of the reduced portion 35 is internally beveled as at 42.

Slidably mounted in the chamber 25 is a piston 45 provided with a counterbored chamber 46 to receive the inner portion of the spring 39 whose inner extremity presses against the inner face 47 of the piston 45. Integral with the forward end of the piston 45 is a head 49 of reduced diameter provided with a rounded or hemispherical end 50 adapted to abut against a conical seat 51 in the valve case 23 concentric with the passage 26 and adapted to close the same. The rear end of the piston 45 is provided with an external bevel or rounded portion 52 adapted to engage the beveled end 42 of the plug 36. When thus engaged the bevel 42 forms a stop for the outward travel of the piston and also cuts off the passage of any fluid which may pass along the exterior of the piston. The spring 39 normally presses the head 49 into its seat 51. The strength of

this spring is determined by the degree of fluid pressure which may be desired to operate the valve.

The upper extension of the case 23 is provided with internal threads 55 engaging threads 56 upon the end of a vertical pipe 57 whose upper end is threaded as at 58 to engage the internally threaded portion 59 of an extension 60 upon the bottom of head 11. This extension is provided with a passage 61 leading from pipe 57 into an annular passage 62 formed in the exterior of a hollow plug 63 frictionally mounted in the head 11 within the cylindrical opening 10 and forming a vacuum chamber 64. Inclined tangential openings 65 lead from the annular passage 62 to the vacuum chamber 64 in the plug 63 adjacent the end of the nozzle. Fixed to or integral with the end of the plug 63 is a plate 66 provided with central perforation 67 in alignment with the nozzle 14.

The operation of the described device is as follows: Liquid passes by gravity through conduit 1 and into nipple 3 to a point slightly below the cap 4. Meanwhile fluid is admitted to the head 11 through conduit 18 and pipes 20 and 57 and the valve case 23. In more detail the fluid passes from the pipe 21 through the opening 24 into the chamber 25 where its advance is cut off by the end 50 of the piston held in its valve seat 51 by the spring 39 thereby closing the opening 26. At a certain determined pressure the fluid in the chamber 25 overcomes the tension of the spring 39 and moves the piston outwardly until its end 52 engages the surface 42 of the plug 37 thereby withdrawing the head 49 from its seat and allowing the fluid to traverse opening 26 and passage 27 into chamber 28. Thence the fluid passes through passages 61, 62, and openings 65 into vacuum chamber 64, escaping through opening 67 and forming a partial vacuum at the end of nozzle 14. This causes the liquid to rise and flow through the pipe 5 and from the end of the nozzle where it is vaporized by the rapid rotation of the fluid through the tangential openings 65.

Referring again to the movement of the piston 45, immediately upon the opening of passage 26 the pressure in chamber 28 is equal to the pressure in the conduit 18 insuring a sufficient pressure of the fluid to completely atomize the liquid drawn from the nozzle 14, thereby insuring that no interval of insufficient fluid pressure shall occur. Immediately upon the falling of the fluid pressure in the conduit 18 the piston head under pressure of the spring closes the opening 26 immediately, shutting off the further flow of fluid through the passage 27 and thus preventing continuation of the action of the fluid upon the liquid at any degree less than the pressure determined as

the minimum at which the liquid can be thoroughly vaporized.

It will be observed that the valve or piston will open at a determined pressure from a source of supply admitting a liquid or fluid to a humidifying, liquid, or other moisture discharging system at the same pressure as that maintained in the source of supply; automatically closing when the liquid or fluid in the source of supply falls below the determined pressure and preventing the flow from the source of supply to the system until the determined or greater pressure is exerted.

Fluid is admitted to the second chamber at 80 and above the pressure at which the valve is opened, so that the pressure in the upper chamber or outlet equals the pressure in the lower chamber. The valve is characterized by the novel capacity absent in check valves, flap valves, or any other valve structures, namely by the avoidance of any differential in pressure between the feed inlet and discharge outlet. It is well known that in the present types of valves the pressure on the discharge side acting upon the rear face of the valve plus the force or agency tending to close the valve, equals the pressure in the feed inlet and upon the receiving face of the valve. In other words, the fluid pressure on the rear face of the valve is less than the pressure on the receiving face of the valve measured by the degree of pressure exerted by the closing agent. This valve as applied in the present instance insures that the fluid is admitted to the chamber 28 immediately upon the opening of the closing agent 50 at the same pressure as that existing in inlet 20; and furthermore the fluid is maintained in chamber 28 at the same pressure as that in inlet 20. The reason why in this case the fluid pressure is maintained equally in the receiving inlet and discharge outlet is because the force of the fluid acts in a direction other than the direction of the normal course of the fluid. The pressure acting on the closing agent is entirely independent of the fluid pressure passing in the normal course into the discharge outlet 28, and the closing agent is in no wise reacted on by the fluid in the discharge chamber, but is controlled by a yielding device of desired strength normally tending to close the passage. Upon this closing agent the fluid pressure from the receiving inlet acts at all times with a pressure equal to the fluid pressure in the receiving inlet itself. Reaction of the fluid is in this case avoided by reason of the fact that at no time does the fluid in the discharge outlet have access to the rear portion of the closing agent which, in the present instance, is shown as a piston.

Both the liquid and fluid inlet pipes are herein described as vertically disposed, and only one vaporizer is shown, but it will be

understood that said pipes may be disposed horizontally or at any desired angle relatively to the conduits, and that the nozzles are arranged as usual in multiple.

5 Neither the fluid compressors nor source of steam is shown, as either are of any usual familiar construction.

What I claim is,—

1. In a device of the type set forth, the combination with the vaporizer and the water inlet member, of a fluid inlet member opening into the vaporizer adapted to admit fluid under pressure to the vaporizer, and means in the fluid inlet member for automatically checking the flow of the fluid to the vaporizer at a determined pressure of the fluid.

2. In a device of the type set forth, the combination with the vaporizer and the water inlet member, of a fluid inlet member communicating with the vaporizer for admitting fluid under pressure to the vaporizer, and means in the fluid inlet member for automatically admitting fluid to the vaporizer only above a minimum determined pressure.

3. In a device of the type set forth, the combination with the vaporizer and the water inlet member, of a fluid inlet member communicating with the vaporizer for admitting fluid under pressure to the vaporizer, and yielding means in the fluid inlet member for automatically controlling the admission of fluid to the vaporizer.

35 4. In a device of the type set forth, the combination with the vaporizer and the water inlet member, of a fluid inlet member communicating with the vaporizer, a casing in the fluid inlet member provided with a piston chamber, a seat in the casing provided with an opening for the passage of a fluid, a piston in the chamber, a head upon the piston adapted to register in the seat, and spring means in the chamber 45 engaging the piston for pressing the head into its seat.

5. In a device of the type set forth, the combination with the vaporizer and the water inlet member, of a fluid inlet member communicating with the vaporizer, a casing in the fluid inlet member provided with a piston chamber disposed at right angles to the fluid inlet member, a seat in the casing provided with an opening to permit the passage of a fluid to the vaporizer, a piston mounted in the chamber, a head upon the piston adapted to register in the seat and close the opening, and means in the piston chamber engaging the piston for 55 forcing the head into its seat at a determined degree of fluid pressure upon the piston.

6. In a device of the type set forth, the combination with the vaporizer and the liquid inlet member, of a fluid inlet member opening into the vaporizer, a casing in the

fluid inlet member provided with a piston chamber and with an opening leading from the piston chamber to the vaporizer, a second opening in the casing leading from the piston chamber to a portion of the fluid inlet member remote from the vaporizer, a piston in the piston chamber adapted to receive against its forward face fluid entering the chamber through the second opening, a head upon the piston adapted to register with the first opening, and a spring in the piston chamber engaging the rear face of the piston and adapted to force the head into the first opening when the fluid pressure upon the piston diminishes. 80

7. In a device of the type set forth, the combination with the vaporizer and the water inlet member, of a fluid inlet member opening into the vaporizer and comprising a casing, a feed pipe leading to the casing, a discharge pipe connecting the casing and the vaporizer, said casing being provided with an intermediate chamber, and having an opening in the casing leading from said chamber to the discharge pipe, and having a second opening leading from the feed pipe to the chamber, and yielding means in the chamber normally closing the first opening adapted to disclose said opening by the pressure of a fluid passing through the second opening. 95

8. In a device of the type set forth, the combination with the vaporizer and the device for feeding moisture thereto, of a casing, a fluid feed pipe opening into one end 100 of the casing, a fluid discharge pipe connecting the casing with the vaporizer, said casing being provided with a piston chamber and with an opening communicating with the piston chamber and with the discharge pipe, and with an opening communicating 105 with the piston chamber and with the feed pipe, a piston mounted in the chamber adjacent the second opening, a head on the piston adapted to register with the first opening, a hollow plug in the casing at the end of the piston chamber, and a spring in the piston chamber abutting against the plug and engaging the piston. 110

9. In a device of the type set forth, the combination with the vaporizer, the liquid inlet member, and the fluid inlet member, of a casing mounted in the fluid inlet member provided with a piston chamber and with an opening for the passage of fluid under pressure, and provided with an extension at right angles to the fluid inlet member and provided with internal threads, a hollow plug provided with a vent opening at one end and with a reduced beveled forward portion having external threads adapted to engage the first mentioned threads, a piston in the piston chamber within the extension provided with a beveled rear margin adjacent the beveled portion of the plug, a head 115 120 125

upon the piston adapted to register with the opening, and a spring inclosed by the extension and the plug pressing against the rear face of the piston.

- 5 10. In a device of the type set forth, the combination with the vaporizer and the water inlet member, of a fluid inlet member communicating with the vaporizer for admitting fluid under pressure to the vaporizer and means in the fluid inlet member for automatically controlling the admission of fluid to the vaporizer.
- 10 11. In a device of the type set forth, the

combination with the vaporizer and the water inlet member, of a fluid inlet member 15 communicating with the vaporizer for admitting fluid under pressure to the vaporizer and yielding means in the fluid inlet member for automatically controlling the admission of fluid to the vaporizer.

20 In testimony whereof I have affixed my signature in presence of two witnesses.

ALBERT J. DRONSFIELD.
